Assor to

The Lowell Manufacturing Company.

Letters Patent N° 1884-Dated Jan'y 19th 1864.

Design for a Carpet Pattern.

~

The schedule referred to in these Letters Pattern and making part of the same.

~~~~~

To all whom it may concern:

Be it known that I, Edemir J. Ney, of Lowell, in the County of Middlesex and State of Massachusetts, have originated and designed a new Pattern for Carpets or other fabrics, of which the following is a full, clear and exact description, reference being had to the accompanying drawings, making part of this specification.

This design consists of combinations of masonic emblems and foliage, arranged in the particular form shown in the drawings.

The colors employed for the different portions of the design, may be varied to suit the taste and wish of the manufacturer.

~ Claim. ~

What I claim as my invention and desire to secure by Letters Patent, is the Design or Pattern for Carpets or other fabrics, herein set forth.
